(57) **CLAIM**

The ornamental design for a movable watering lip, as shown and described.

DESCRIPTION

FIG. 1 is a perspective view of a movable watering lip shown from the side and up for convenience of illustration; FIG. 2 is a side view of movable watering lip with a pot shown in broken lines.

FIG. 3 is a right side view of FIG. 1;

FIG. 4 is a left side view of FIG. 1;

FIG. 5 is a top plan view of FIG. 1;

FIG. 6 is a bottom plan view of FIG. 1;

FIG. 7 is a front elevational view of FIG. 1; and,

FIG. 8 is a back elevational view of FIG. 1.

The broken line showing of environmental structure is for illustrative purposes only and forms no part of the claimed design.
